UNITED STATES PATENT OFFICE.

ROLLAND M. BICKERSTAFF, OF NEW YORK, N. Y., ASSIGNOR TO NATIONAL PRINTING AND ENGRAVING CO., OF CHICAGO, ILLINOIS, A CORPORATION OF ILLINOIS.

DISPLAY-CARD.

1,236,253.

Specification of Letters Patent. Patented Aug. 7, 1917.

Application filed January 22, 1917. Serial No. 143,606.

To all whom it may concern:

Be it known that I, ROLLAND M. BICKERSTAFF, a citizen of the United States, and a resident of the city, county, and State of 5 New York, have invented certain new and useful Improvements in Display-Cards, of which the following, when taken in connection with the drawing accompanying and forming a part hereof, is a full and complete 10 description.

This invention relates to an advertising device designed to exhibit the whole or part of a person, object, or thing in a manner or form to attract attention, independently of 15 the text accompanying the same; said device being adapted to be set on a counter, shelf, or other horizontal table which serves as a base therefor.

The objects of the invention are to so construct and mark a sheet of card board, thick paper, or other thin and ductile material, that the same may be bent on a determined line to form the sides of a triangle of which the substantially horizontal table on which 25 it is placed will form the base, and to secure said sides in said relative position.

Further objects are to cut out or cut around a portion of the body of the side which is intended to form the back of display device 30 obtained; so that such cut out portion will be and remain in the same plane as the part forming the front or display side of the device.

A further object is to so construct the device that the holding part, by means whereof the sides of the set up device are held in suitable relative position, will be obtained from the body of the part forming the back thereof, by cutting around the outline of the 40 sides and one end of said latch and bending it out from said body on the remaining and attached end.

A further object is to provide said latch with locking means, obtained from the body 45 of the latch, and adapted to maintain it in determined engagement, in case the device be overturned or otherwise misplaced.

Further objects are to obtain a device of the character recited, which is easily "set 50 up" by one not particularly skilled in mechanics, as say a clerk or proprietor of a store, or warehouse; to obtain a device which is "taking" in appearance; economically made; not liable to be injured when slipped

in quantities, or when mounted singly on a table for display.

A construction embodying this invention is illustrated in the drawing referred to, in which Figure 1 represents a top plan view of the blank properly cut (but not set up) to 60 form the device.

Fig. 2 is an end view of the blank illustrated in Fig. 1.

Fig. 3 is a front view of the device set up for use and 65

Fig. 4 is an end view thereof.

A reference character applied to designate a given part indicates said part throughout the several figures of the drawing wherever the same appears. 70

A indicates a sheet of card board, straw board, thick paper, or other suitable sheet material. B illustrates a cut through sheet A, as by a die, on the outline of so much of the object on said sheet which is to be displayed as a cut-out, (in the example illustrated being the head and shoulders of a woman) and which is obtained from the part, (b), of said sheet constituting the back of the "set up" card. C is a line which indicates the location of the bend or break which is made when the device is "set up." This cut out portion of the object displayed is indicated by the reference letter D, and is designed to remain in the same plane as 80 part b of said sheet A. 80

E represents a latch member which is cut out (on three sides thereof) from the body of part b of the sheet as indicated by the line which is lettered F. e, e, are lugs at 90 the free end of latch member E. G represents the line on which latch member E is bent out from the body of the sheet when the device is "set up." H, H, represent recesses in the sides of latch member E. I 95 represents a tongue in member E which is obtained by a cut through said member on the line lettered J. j is the line on which tongue I may be bent out from the body of said tongue. 100

K is an open beveled notch, or recess at the end L of part b of the sheet A. Said part b forms the front and display side of said sheet when the device is set up. The narrow part or portion of notch K, which 105 is positioned on the edge L of sheet A, is sufficiently wide to admit the insertion in said notch of the recessed part of latch

member E and the widest part of the notch admits the remainder of said latch therein.

In setting up the device, sheet A is bent on line C, and latch member E is inserted 5 in notch K, in the manner last above recited, and said latch member is then drawn back, in said notch, as far as the lug e, e, will permit. Tongue I is then forced out from latch E to come in contact, at its free 10 end, with the back of the front of the bent up sheet. Latch member E is thereby locked in notch or recess K.

When set as above described the display card can be placed with the ends L, L' there- 15 of on any suitable table, in the position which is illustrated in Figs. 3 and 4.

Where it is not desired to lock latch member E in notch K the tongue I is not re- quired.

20 When the sheet A is made of material which is easily broken when bent, said sheet is reinforced by the flexible strips M and N, (or one thereof), which are adhesively joined to the back of said sheet.

25 A duplicate latch member E, and a duplicate notch K are at times cut out from the body part b of the sheet on the opposite side of said part b from the one which is illus- trated.

30 I claim.—

1. A display card comprising a sheet of suitable material provided with means to indicate a determined line on which to bend said sheet, a latch member cut from and 35 adapted to be bent out of the body of said sheet, said latch member provided with re- cesses on the sides thereof and with lugs on said sides positioned at the free end of said member, and said sheet provided with a 40 notch at one end thereof arranged to co-act with said latch member, the open end of said notch adapted to permit the recessed part of said member to be inserted therein, the widest part of said notch adapted to admit 45 the non-recessed portion of said member and said lugs arranged to prevent said member from being drawn out from said notch.

2. A display card comprising a sheet of suitable material provided with means to 50 indicate a determined line on which to bend said sheet, a latch member cut from and adapted to be bent out of the body of said sheet, a tongue on said latch member, and said latch member provided with recesses on 55 the sides thereof and with lugs on said sides positioned at the free end of said member, and said sheet provided with a notch at one

end thereof arranged to co-act with said latch member, the open end of said notch adapted to permit the recessed part of said member to be inserted therein, the widest part of said notch adapted to admit the non- recessed portion of said member and said lugs arranged to prevent said member from being drawn out from said notch, the said tongue adapted to be forced out from said body of the latch member to lock it in said notch.

3. A display card comprising a sheet of suitable material provided with means to 70 indicate a determined line on which to bend said sheet, a latch member cut from and adapted to be bent out of the body of said sheet, said latch member provided with re- cesses on the sides thereof and with lugs 75 on said sides positioned at the free end of said member, and said sheet provided with a notch at one end thereof arranged to co- act with said latch member, the open end of said notch adapted to permit the recessed 80 part of said member to be inserted therein, the widest part of said notch adapted to admit the non-recessed portion of said mem- ber and said lugs arranged to prevent said member from being drawn out from said 85 notch, in combination with flexible strip adhesively joined to the back of said sheet to reinforce said sheet on the lines indicat- ing bends.

4. A display card comprising a sheet of suitable material provided with means to 90 indicate a determined line on which to bend said sheet, and provided with a cut out member from the body of the sheet, the cut to obtain said member commencing between 95 the ends of said line, a latch member cut from and adapted to be bent out of the body of said sheet, said latch member, provided with recesses on the sides thereof and with lugs on said sides positioned at the free end 100 of said member, and said sheet provided with a notch at one end thereof arranged to co-act with said latch member, the open end of said notch adapted to permit the recessed part of said member to be inserted 105 therein, the widest part of said notch adapted to admit the non-recessed portion of said member and said lugs arranged to prevent said member from being drawn out from said notch.

ROLLAND M. BICKERSTAFF.
